UNITED STATES PATENT OFFICE.

JOHANNES F. W. KOLVIG, OF BRIDGEPORT, CONNECTICUT, ASSIGNOR TO THE LAKE TORPEDO BOAT COMPANY, OF BRIDGEPORT, CONNECTICUT, A CORPORATION OF MAINE.

HYDROPLANE-OPERATING MECHANISM FOR SUBMARINE BOATS.

Application filed January 12, 1922. Serial No. 528,691.

To all whom it may concern:

Be it known that I, JOHANNES F. W. KOLVIG, a citizen of the United States, residing at Bridgeport, in the county of Fairfield and 5 State of Connecticut, have invented a certain new and useful Improvement in Hydroplane-Operating Mechanism for Submarine Boats, of which the following is a full, clear, and exact description.

Submersible boats are controlled in part when submerging or rising by means of hydroplanes. These hydroplanes are pivotally and tiltably mounted to be extended, into operative position, or folded into inoperative position, or to present either face to the action of the passing waters to cause the boat to submerge or to rise. Independent mechanisms are usually required and provided for extending and folding, and for 10 tilting such hydroplanes. It is the object of this invention to provide means whereby the several adjustments of the hydroplanes may be effected by a single mechanism, so that the hydroplanes may be extended, or folded, 15 and tilted when extended by a continued manipulation of the same member initially operated to extend the hydroplanes.

The invention consists of pillow blocks mounted within the boat; cylinders mounted 20 within the pillow blocks and having a limited rotary movement; plungers mounted within the cylinders to reciprocate therein and to have a limited independent rotary movement; plugs having screwthread connection with the plungers; hydroplanes pivotally connected to the cylinders; link connections between the hydroplanes and plugs; stop means to limit the unfolding of the 25 hydroplanes when extended into operative position; clutch means between the hydroplanes and the plungers to insure a firm connection and a positive turning of the hydroplanes with the plungers when the latter are rotated to tilt the hydroplanes to the desired 30 angle to cause the boat to submerge, or to rise, and guide means for the cylinders and plungers, so combined and arranged, as hereinafter explained, as to attain the stated object.

In the accompanying drawings, illustrating the invention, in the several figures of which like parts are similarly designated, Figure 1 is a transverse section of part of a submarine boat provided with hydroplane-

operating mechanism embodying the invention, parts being broken away to show portions in section and bring out more clearly the relation of the elements, the hydroplanes being folded. Fig. 2 is a detail central longitudinal section on a larger scale, the hydroplane being extended, the plug at the limit of its forward movement, and the plunger at the point in its forward travel to have a combined longitudinal and rotary movement imparted thereto during the remainder of its forward travel. Fig. 3 is a view similar to Fig. 2 showing the position of the parts when the plunger is at the limit of its outward travel in the cylinder and in clutched engagement with the hydroplane. Fig. 4 is a transverse section drawn on the line $x-x$ of Fig. 3. Fig. 5 is a detail horizontal section about on the line $y-y$ of Fig. 3. Fig. 6 is a view similar to Fig. 4 showing the cylinder and plunger turned to tilt the hydroplane into submerging position. Fig. 7 is a perspective view of the cylinder.

In the embodiment of the invention illustrated, the pillow blocks 1 are shown mounted upon a plate or deck 2 within the sides 80 of the superstructure 3 of a submarine boat, the hull or body of the boat being indicated at 4. The pillow blocks may be of any desired construction best adapted for the particular application of the invention.

A cylinder 5 is mounted in each of the pillow blocks, and is flanged at its outer end as indicated at 6, and formed with outwardly extending lugs 7 to which the hydroplane is pivotally connected in a manner hereinafter 90 explained. Longitudinal slots 8 are formed in the sides of the cylinder 5 at diametrically opposite points and constitute guide-ways in which lugs 9 are adapted to travel. These lugs are shown vertical in Figs. 1, 2 and 3 for clearness sake, but Figs. 4 and 5 show their actual location on the cylinder and pillow blocks, namely, horizontal. A hollow 95 guide extension 10 is connected to the inner end of each of the cylinders 5 and is formed upon its inner walls at diametrically opposite points with longitudinally disposed grooves or guide-ways 11, in which lugs 12 are adapted to operate. The hollow guide extension 10 is of less diameter than the cylinder 5, and is secured thereto by means of a screwthread connection.

A plunger is mounted in each of the cyl-

inders 5 and comprises a head 13 and a stem 14, the latter being of a diameter to enter the hollow extension 10, and the head 13 being of a diameter to fit within the cylinder 5. Lugs 12 are formed upon opposite sides of the stem 14 of the plunger, and are located some distance from the inner end of the stem, so that when the lugs 12 clear the guide-ways 11, the inner portion 10 of the stem 14 obtains a bearing within the hollow guide extension 10, thereby assisting materially in retaining the plunger in proper position and preventing its binding within the cylinder. The stem 14 is 15 hollow, and an end portion thereof is formed with internal screwthreads 15, which mesh with corresponding screwthreads 16 formed upon the outer end of a shaft 17, which is mounted in the hollow 20 guide extension 10, and is formed with an outwardly disposed annular collar 18 entering a corresponding annular groove in the bearing portion of the hollow extension 10. The latter is fitted with a threaded cap 19 25 which holds the shaft 17 from any longitudinal movement. The screwthreads 15 and 16 are of high pitch to insure a relatively long movement of the plunger while imparting a comparatively small rotary 30 movement to the shaft 17. The head 13 of the plunger is centrally recessed, and internally screwthreaded, as indicated at 20. This head is likewise formed in its outer side with an annular groove 21 in which is 35 fitted a yoke ring 22, the latter being provided with the lugs 9, which are of a length to operate in the guide-ways 8 of the cylinder and similar guide-ways 23 formed in the sides of the pillow blocks or casings 1 in 40 position to register with the guide-ways 8. This yoke is split in order to assemble it, and its parts are held together by bolts or screws 22^x.

The location of the guide-ways 8 and 23 45 is immaterial, but, in practice, such guide-ways will be disposed to be in the plane of the joint formed between the body of the pillow block and its cap plate. For convenience the guide-ways 8 and 23 are shown in 50 Figs. 1, 2, and 3, as being vertically disposed, but in practice they will occupy a horizontal position, as indicated in Figs. 4 and 5, as previously stated.

A plug 24 is provided for each of the 55 plungers and is exteriorly threaded to match the internal screwthreads 20 formed in the recess in the head of the plunger. When the hydroplane is folded against the side of the boat, the plug 24 occupies a position 60 at the outer end of the recess formed in the head of the plunger, as shown most clearly in Fig. 1, but when the hydroplane is extended into operative position and is clutched to the plunger so as to turn there- 65 with, the plug 24 occupies a position at the

inner end of the plunger as indicated most clearly in Fig. 3. When the plunger is traveling outward in the cylinder 5 to extend the hydroplane into operative position, the plug 24 moves therewith, but when 70 the hydroplane is fully extended into operative position, a continued outward movement of the plunger is effected simultaneously by a rotary movement thereof, the plunger advancing with reference to the 75 plug 24 by reason of the screwthread connection between the plug and plunger. This combined longitudinal and rotary movement of the plunger results in bringing into operation a clutch mechanism between the 80 plunger and hydroplane to insure a positive turning of the hydroplane with the plunger and cylinder. During the outward movement of the plunger within the cylinder 5, the plunger is held from turning by the 85 lugs 12 traveling in the guide-ways 11, but when the plug 24 reaches the limit of its outward movement with the plunger, the guide lugs 12 clear the guide-ways 11, and thereby admit of the plunger turning, and, 90 at the same time, continuing to advance to bring the clutch mechanism between the hydroplane and the plunger into operation.

The plunger is caused to turn by reason of the screwthread connection 20 between it 95 and the plug 24, and the turning movement is somewhat assisted by the screwthread connection between the plunger and the shaft 17. The cylinder 5 remains stationary throughout the forward travel of the 100 plunger by means of the lugs 9 operating in the guide-ways 23 and 8. The yoke 22 has a relative turning movement on the head of the plunger, but moves with the latter to admit of its lugs 9 traveling in the guide-ways 8 and 23. The yoke 22, with its lugs 9, constitutes holding means to prevent rotation of the cylinder 5 during the combined 105 longitudinal and rotary movement of the plunger. When the plunger reaches the 110 limit of its forward movement, the yoke ring 22 has advanced to cause its lugs 9 to clear the guide-ways 23 of the pillow block, or like fixed bearing 1, and register with 115 slots or clearance-ways 25 extending laterally from the outer ends of the guide-ways 23. The laterally extending slots, or clearance-ways 25, project in opposite directions from the guide-ways, as indicated most clearly in Figs. 4 and 6. At the moment 120 the plunger reaches the limit of its forward movement, the clutch between the plunger and hydroplane is completely engaged, and the lugs 9 register with the slots, or clearance-ways 25, hence a continued rotation of 125 the shaft 17 causes the plunger, cylinder, and hydroplane to turn, whereby the inclination of the hydroplane may be reversed to admit of the boat submerging.

The hydroplane is indicated at 26, and 130

may be pivotally connected to the cylinder 5 in any desired and substantial manner to admit of it swinging outward into operative position, and inward into folded position, 5 and turning with the cylinder when the latter is rotated about its longitudinal axis. As illustrated, the hydroplane 26 is carried by means of an arm 27 to which it is attached in any desired way. The arm 27 is 10 pivotally connected to the lug 7 by means of a suitable connection 28. The heel of the arm 27 is broadened and terminates in projections 29 and 30, which are spaced apart. The projection 30 is, in effect, a stop, and 15 engages the outer face of the flange end 6 of the cylinder 5, thereby limiting the outward and downward movement of the hydroplane when swung into operative position. The stop 30 relieves all the internal mechanism 20 and the shaft 17 of all strain, and holds the hydroplane when extended against downward thrust upon its upper face. The projection 29 is essentially a clutch element, and cooperates with a lip 31 projecting out- 25 wardly from the head 13 of the plunger, such lip forming the companion clutch element. The clutch element 29 engages the inner face of the clutch element 31 when the clutch is engaged, as shown most clearly in 30 Fig. 3. The space 32, separating the clutch element 29 from the stop 30, receives the clutch element 31, and it will thus be understood that the clutch element 31 cooperates with both projections 29 and 30 to secure a 35 firm connection between the plunger and hydroplane so as to secure a locking effect which, similarly to the lower projection 30, keeps the hydroplane from folding back, and thereby relieves the mechanism from 40 strain. Also, by the pressure exerted, either upwards or downwards, by the water acting on the hydroplane when tilted in any direction, this clutching feature helps to keep the mechanism from any tendency of loosening 45 or rattling, in short, locks it securely in place against folding or extending any further while the hydroplane is being rotated back and forth within the limiting angles of rise or dive. 50 A link 33 forms connecting means between the hydroplane and plunger, and is pivotally connected at its outer end to the heel of the arm 27, and at its inner end to the plug 24. When the plunger is at the limit of its 55 inner movement within the cylinder 5, the hydroplane 26 is folded against the side of the boat into shipped position (Fig. 1). When the hydroplane is extended into operative position, the plunger and the plug 24 60 carried thereby, occupy a position at the outer or forward end of the cylinder (Figs. 2 and 3). The plunger receives a greater movement within the cylinder than the plug, this being due to the fact that the plug 24 65 ceases to move forward when the hydroplane

is fully extended and the stop 30 comes in contact with the outer end 6 of the cylinder 5. When the plug 24 ceases to move forward, the plunger continues to advance by a combined rotary and longitudinal movement to bring the clutch mechanism between the plunger and hydroplane into action, and to bring the yoke 22 into position so that its lugs 9 will register with the lateral slots or clearance-ways 25, thereby releasing the cylinder 5 so that the plunger and cylinder may turn to tilt the hydroplane to cause the boat to submerge or rise as desired by varying the angle of tilting. These several operations are effected by rotation of the shaft 17 in 70 one direction, as to the right. 75

It should be stated that the parts are so disposed that when the hydroplane is initially extended into operative position, it is tilted so that its lower face is inclined upwardly and forwardly, causing a rising effect of the bow, thereby preventing premature submerging of the boat when driven forward. To cause the boat to submerge, it is necessary to tilt the hydroplane to cause its 80 upper face to incline upwardly and rearwardly, whereby the boat is depressed by the action of the passing waters upon the upper face of the hydroplane. 85

It is to be understood that the disposition 90 of the guide-ways 23 controls the relative normal position of the cylinder 5 and the hydroplane pivoted thereto, since the lugs 9 of the yoke 22 travel in the guide-ways 8 and 23 during the longitudinal movement of the plunger within the cylinder, hence the relative position of the hydroplane during its extending and folding movements may be predetermined. When the guide-ways 23 95 extend parallel with the longitudinal axis of the cylinder, the hydroplane is inclined normally to the horizontal during its folding and unfolding, with the result that when the hydroplane is extended into operative position, it is inclined so as to present its lower face to the action of the waters when the boat is in forward movement to prevent premature submergence thereof, and to cause the boat to submerge, it is necessary to tilt the hydroplane to a reverse inclination. By 100 inclining the guideways 23 in opposite directions, it is possible to fold the hydroplane against the side of the boat so that its pivotal axis is parallel with a longitudinal and horizontal plane, and when extended into 105 operative position, the hydroplane is tilted so as to have a rising effect, as previously stated. By this arrangement, the hydroplane is adapted to fold square against the side of the boat so as to present a somewhat 110 better appearance. 115

The shaft 17 has its opposite end portions reversely screwthreaded on port or starboard sides, as indicated most clearly in Fig. 1, and may be operated from any suitable source of 120 125 130

power. As indicated, a worm gear 34 is secured to the shaft 17 and meshes with a worm 35 forming part of a drive shaft 36. When the drive shaft 36 is operated, the shaft 17 is rotated, and by reason of its screwthread connections with the plungers of the oppositely disposed hydroplane mechanisms, the latter are actuated simultaneously by a like movement to project the hydroplanes into operative position, to tilt such hydroplanes, when extended, to the required angle to cause the boat to submerge, to go level, or to rise, or to fold the hydroplane against the sides of the boat into shipped position.

As shown in Fig. 1, the shafts 17 may be connected to turn together, as by the coupling 37, shown as a universal joint.

It will thus be understood that the various movements are effected with certainty and in a positive manner by means of a single operating part, as the shaft 17.

The invention provides a mechanism embodying comparatively few parts, and which is certain and positive in action, efficient and reliable in operation, and not susceptible to derangement or necessitating frequent repairs or replacements. Moreover, the construction and arrangement are such as to admit of ready access to the parts for inspection, adjustment, or other required purpose. Also, if desired, the clearance-ways or slots 23 and 25, in the pillow block, may be encased from the outside by means of plates or other suitable means, which together with the stuffing box mentioned would prevent any water entering into the interior of the ship through the mechanism.

The ends of the extension 19 may be provided with stuffing boxes, thereby making the whole mechanism watertight and pressure proof if desired, so as to enable the use of this mechanism projecting through the ship's hull into the interior of any part of the ship, in which latter case each pillow block would be provided with a flange, whereby it would be connected to the side of the ship.

Other variations than those suggested may be made within the principle of the invention and the scope of the claims following.

What I claim is:—

1. In a submarine boat, folding and tilting hydroplanes, and operating mechanism therefor, including a main member mounted to receive a reciprocating movement when extending or folding the hydroplanes, and a combined longitudinal and rotary movement when reaching the limit of its outward travel.

2. In a submarine boat, folding and tilting hydroplanes, and operating mechanism therefor, including a main member mounted to receive a reciprocating movement when extending or folding the hydroplanes, and a

combined longitudinal and rotary movement when reaching the limit of its outward travel, and a second member connected with the hydroplane and having screw-thread connection with the main member and adapted to remain stationary during the combined longitudinal and rotary movement of said main member.

3. In a submarine boat, rotatable members, hydroplanes pivotally supported by the rotatable members, plungers mounted within the rotatable members to reciprocate therein and to receive a combined rotary and longitudinal movement when reaching the limit of their outward travel, members connected with the respective hydroplanes and having screwthread connection with the plungers, and clutch devices between the plungers and hydroplanes brought into active operation during the final outward movement of the hydroplane.

4. In a submarine boat, members mounted to turn about their longitudinal axes, hydroplanes pivotally supported by said members, means for extending and folding the hydroplanes, and stops connected with the hydroplanes and adapted to engage the outer ends of the members pivotally supporting the hydroplanes.

5. In a submarine boat, rotatable members, hydroplanes pivotally supported by said rotary members, plungers having connection with the respective hydroplanes for extending and folding them, and clutch elements between the plungers and hydroplanes brought into active operation when the plungers are at the limit of their outward movement.

6. In a submarine boat, folding hydroplanes, rotatable members pivotally supporting the hydroplanes, plungers mounted within the members to reciprocate therein and having a combined longitudinal and rotary movement at the outward limit of their travel, and members having link connection with the hydroplanes and screwthread connection with the respective plungers and held stationary when the hydroplanes are extended into operative position and during the combined longitudinal and rotary movement of the plungers.

7. In a submarine boat, folding hydroplanes, rotatable members pivotally supporting the hydroplanes, plungers mounted within the members to reciprocate therein and having a combined longitudinal and rotary movement at the outward limit of their travel, members having link connection with the respective plungers, and held stationary when the hydroplanes are extended into operative position and during the combined longitudinal and rotary movement of the plungers, and cooperating clutch elements having connection with the hydroplanes and plungers and brought into active engage-

ment during the final outward movement of the plungers.

8. In a submarine boat, folding hydroplanes having stop and clutch elements associated therewith, rotatable members having the hydroplanes pivotally connected therewith, the hydroplanes when extended having their stop elements in engagement with the rotary members, plungers having connection with the respective hydroplanes to effect a pivotal movement thereof, and clutch elements associated with the plungers and adapted to engage the clutch elements of the hydroplanes.
9. In a submarine boat, pivotally and tiltably mounted hydroplanes, rotatable supports therefor, plungers mounted within the rotatable supports to have a reciprocating movement and a combined longitudinal and rotary movement, plugs having screwthread connection with the plungers and link connection with the hydroplanes, and means for holding the rotatable supports stationary during the longitudinal movement of the plungers and releasing the rotatable supports when the plungers are at the limit of their outward movement to admit of the plungers and rotatable supports turning about a longitudinal axis to tilt the hydroplanes.
10. In a submarine boat, folding and tiltting hydroplanes, rotary supports therefor, plungers having connection with the respective hydroplanes and adapted to receive reciprocating movement and a combined longitudinal and rotary movement when reaching the limit of their forward travel, and holding means movable with the plungers to prevent rotation of the said rotary supports during the reciprocating movements of the plungers and adapted to release the supports when the plungers are at the limit of their forward travel to admit of the said supports turning to tilt the hydroplanes.
11. In a submarine boat, folding and tiltting hydroplanes, rotary supports therefor, plungers having connection with the respective hydroplanes and adapted to reciprocate within the supports and to receive a combined rotary and longitudinal movement when reaching the limit of their outward travel, guide means between the plungers and rotary supports, and holding means movable with the plungers and acting to prevent rotation of the rotary supports during the reciprocating movements of the plungers and adapted to release the supports when the plungers are at the limit of their forward travel to admit of the supports turning to tilt the hydroplanes.
12. In a submarine boat, folding and tiltting hydroplanes, bearings, supports for the hydroplanes rotatably mounted in the bearings, there being corresponding longitudinally disposed guide-ways in the bearings
- and supports, plungers mounted within the rotary supports and adapted to reciprocate therein and to receive a combined longitudinal and rotary movement when reaching the limit of their forward travel, guide means between the plungers and supports to hold them in predetermined position during the reciprocating movements of the plungers and adapted to release the plungers to admit of their combined longitudinal and rotary movement, and holding means movable with the plungers and operating in the guide-ways of the supports and bearings and adapted to clear the guide-ways of the bearings when the plungers are at the limit of their forward travel to admit of the plungers and supports turning in the bearings to tilt the hydroplanes.
13. In a submarine boat, folding and tiltting hydroplanes, rotary supports for the hydroplanes and having longitudinal guide-ways, bearings receiving the rotary supports and provided with guide-ways in coincident position with the guide-ways of the supports, plungers mounted to reciprocate within the supports and having connection with the hydroplanes, guide means between the plungers and rotary supports, and holding means movable with the plungers and adapted to operate in the guide-ways of the supports and bearings and adapted to clear the guide-ways of the bearings when the plungers are at the limit of their forward travel to admit of the plungers and rotary supports turning to tilt the hydroplanes.
14. In a submarine boat, folding and tiltting hydroplanes, rotary supports therefor provided with longitudinal guide-ways registering with the longitudinal guide-ways of the supports, the guide-ways of the bearings having laterally extending clearance-ways at their forward ends, plungers mounted to reciprocate within the rotary supports and having connection with the hydroplanes, and holding means movable with the plungers and adapted to operate in the guide-ways of the supports and bearings to prevent turning of the supports during the folding and unfolding of the hydroplanes and adapted to register with the clearance-ways when the plungers are at the limit of their forward travel to admit of the turning of the rotary supports to tilt the hydroplanes.
15. In a submarine boat, folding and tiltting hydroplanes, rotary supports therefor provided with two sets of longitudinally disposed guide-ways, bearings for the rotary supports having guide-ways in coincident position with one set of guide-ways of the supports, plungers mounted to reciprocate within the supports and having guide elements cooperating with the remaining guide-ways of the supports, and having connection with the hydroplanes, and hold-

- ing means movable with the plungers and adapted to operate in the registering guide-ways of the supports and bearings when the plungers are at the limit of their forward travel.
16. In a submarine boat, folding and tilting hydroplanes, rotary supports therefor, bearings receiving the supports, said bearings and supports having corresponding guide-ways and the guide-ways of the bearings having laterally extending clearance-ways, plungers mounted to reciprocate within the supports and adapted to receive a combined longitudinal and rotary movement when reaching the limit of their forward travel, cooperating guide means between the plungers and rotary supports, plugs having connection with the hydroplanes and screw-thread connection with the respective plungers, and holding means movable with the plungers and adapted to operate in the guide-ways of the supports and bearings to register with the clearance-ways of the bearings when the plungers are at the limit of their forward travel to admit of the supports turning to tilt the hydroplanes.
17. In a submarine boat, folding and tilting hydroplanes, rotary supports therefor, plungers mounted to reciprocate within the supports and adapted to receive a combined rotary and longitudinal movement when reaching the limit of their forward travel, connecting means between the plungers and hydroplanes, and a single shaft having screwthread connection with the plungers and adapted to effect a simultaneous movement thereof to fold or unfold the hydroplanes and to tilt such hydroplanes when extended into operative position.
18. In a submarine boat, folding and tilting hydroplanes, rotary supports therefor, plungers mounted to reciprocate within the supports and to turn therewith when reaching the limit of their forward travel, and clutch means between the plungers and hydroplanes to insure a firm connection between them during the turning of the plungers about their axes to tilt the hydroplanes.
19. In a submarine boat, folding and tilting hydroplanes, rotary supports therefor, plungers mounted to reciprocate within the supports and to turn therewith when at the limit of their forward travel, plugs having screwthread connection with the plungers, connecting means between the plugs and hydroplanes, and clutch mechanism between the plungers and hydroplanes to obtain a firm connection between such parts to insure turning of the hydroplanes and plungers when tilting the hydroplanes into submerging or rising position.
20. In a submarine boat, bearings disposed within the sides of the boat, cylinders rotatably mounted in the bearings, the cylinders and bearings having registering lon-
- gitudinally disposed guide-ways, hydroplanes pivotally supported by the cylinders, plungers mounted to reciprocate within the cylinders, cooperating clutch elements associated with the hydroplanes and plungers, and members having connection with the hydroplanes and screwthread-connection with the respective plungers.
21. In a submarine boat, bearings arranged within the sides thereof, cylinders mounted in the bearings and having a limited rotary movement, hydroplanes pivotally supported by the cylinders, plungers mounted to reciprocate within the cylinders and adapted when at the limit of their forward movement to make firm engagement with the hydroplanes, connecting means between the hydroplanes and plungers and having a limited movement with respect to the plungers, and holding means movable with the plungers and adapted to engage the cylinders and bearings for releasing the cylinders when the plungers are at the limit of their outward travel to admit of the plungers and cylinders turning in unison to tilt the hydroplanes into submerging position.
22. In a submarine boat, bearings arranged within the sides of the boat and having longitudinal guide-ways and lateral clearance-ways at the outer ends of the longitudinal guide-ways, cylinders rotatably mounted in the bearings and formed with longitudinal guide-ways in register with the guide-ways of the bearings, folding and tilting hydroplanes supported by the cylinders, plungers mounted to reciprocate within the cylinders, plugs having screwthread connection with the plungers and connected with the hydroplanes, clutch elements associated with the hydroplanes and plungers and brought into active engagement when the plungers are at the limit of their outward travel, and holding means movable with the plungers and adapted to operate in the guide-ways of the cylinders and bearings and to register with the clearance-ways of the bearings when the plungers are at the limit of their forward travel to admit of the cylinders and plungers turning together when tilting the hydroplanes into submerging position.
23. In a submarine boat, bearings mounted within the sides of the boat and provided with longitudinal guide-ways terminating at their forward ends in laterally extending clearance-ways, cylinders rotatable in the bearings and formed with longitudinal guide-ways to register with the guide-ways of the bearings, hydroplanes pivotally supported by the cylinders, plungers mounted to reciprocate in the cylinders and to receive a combined longitudinal and rotary movement when reaching the limit of their forward travel, plugs having screwthread connection with the plungers, links connecting

- the plugs with the hydroplanes, guide means between the plungers and the cylinders, holdings means movable with the plungers and adapted to operate in the registering 5 guide-ways of the cylinders and bearings and adapted to register with the clearance ways of the bearings when the plungers are at the limit of their forward travel, stops associated with the hydroplanes to engage 10 the outer ends of the cylinders and hold the hydroplanes extended in operative position, and clutch elements associated with the hydroplanes and plungers and in operative engagement when the plungers are at the limit 15 of their forward travel.
24. In a submarine boat, bearings mounted within the sides of the boat and provided with longitudinal guide-ways and laterally extending clearance-ways, cylinders rotatable in the bearings and formed with longitudinal guide-ways, hydroplanes pivoted to the cylinders, plungers mounted to reciprocate within the cylinders and to receive a combined rotary and longitudinal move- 20 ment, connecting means between the hydroplanes and plungers, and yokes loosely mounted upon the plungers and having outwardly extending portions to operate in the guide-ways of the cylinders and plungers.
25. In a submarine boat, pillow blocks having longitudinal guide-ways and later- 25

ally extending clearance-ways, cylinders rotatable in the pillow blocks and provided with hollow extensions in axial line therewith, the cylinders and their hollow exten- 30 sions being provided with longitudinal guide-ways, hydroplanes pivoted to the cylinders, plungers embodying head and stem portions to operate in the cylinders and hollow extensions, respectively, the stem por- 35 tions being provided with guide lugs to operate in the guide-ways of the said hollow extensions, plugs having screwthread connection with the heads of the plungers and connected by means of links with the hydro- 40 planes, yokes loosely connected with the heads of the plungers and having offstand- 45 ing portions to operate in the guide-ways of the cylinders and pillow blocks, stops connected with the hydroplanes extended in operative position, and clutch elements associated with the hydroplanes and plungers and brought into active operation when the plungers are at the limit of their forward travel. 50

55 In testimony whereof I have hereunto set my hand this 27 day of December A. D. 1921.

JOHANNES F. W. KOLVIG.
